Primary Examiner — Kendra Leslie Hamilton(74) *Attorney, Agent, or Firm* — Westbridge IP LLC(57) **CLAIM**

The ornamental design for a teething toy, as shown and described.

DESCRIPTION

FIG. 1 is a front perspective view of a teething toy showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 of FIG. 1; and,

FIG. 10 is an enlarged view of portion 10 of FIG. 1.

The broken lines in the drawings illustrate the portions of the teething toy which form no part of the claimed design.

1 Claim, 10 Drawing Sheets(56)
